UNITED STATES PATENT OFFICE

105,501

DESIGN FOR A COMBINATION STAPLING MACHINE AND DESK UNIT

Roy E. Peterson, Norwalk, Conn., assignor to
The E. H. Hotchkiss Company, Norwalk, Conn.,
a corporation of Connecticut

Application December 16, 1936, Serial No. 66,564

Term of patent 7 years

To all whom it may concern:

Be it known that I, Roy E. Peterson, a citizen of the United States, residing at Norwalk, county of Fairfield, State of Connecticut, have invented a new, original, and ornamental Design for a Combination Stapling Machine and Desk Unit, of which the following is a specification, reference being had to the accompanying drawing, forming part thereof.

The figure is a perspective view of a combination stapling machine and desk unit, showing my new design.

I claim:

The ornamental design for a combination stapling machine and desk unit, substantially as shown.

ROY E. PETERSON.
